UNITED STATES PATENT OFFICE.

MINARD F. WOOD, OF WORCESTER, MASSACHUSETTS.

BLUING DEVICE.

No. 872,879.

Specification of Letters Patent.

Patented Dec. 3, 1907.

Application filed September 2, 1905. Serial No. 276,815.

To all whom it may concern:

Be it known that I, MINARD F. WOOD, a citizen of the United States of America, residing at Worcester, in the county of Worcester and State of Massachusetts, have invented new and useful Improvements in Bluing Devices, of which the following is a specification.

This invention relates to improvements in bluing devices for use in bluing rinsing water in the process of washing clothes.

The object of the invention is to provide a bluing device which is simple and effective in construction and adapted to be operated without soiling the hands, clothes, or surrounding objects, and which will diffuse the coloring material without sediment and liability of spotting the clothes, and insures convenience and economy in the use of the bluing material.

A further object of the invention is to provide a bluing device wherein the handle is made to subserve the function of a storage chamber or reservoir in which a desired quantity of the bluing material in any preferred form may be kept for use, so that the bluing holder may be conveniently replenished when occasion requires.

In the accompanying drawing illustrating the invention,—Figure 1 is a side elevation of a bluing device embodying my invention; and Fig. 2 is a longitudinal section of the same.

Referring now more particularly to the drawing, the numeral 1 represents a handle, preferably of wood and of ordinary form and provided at its forward end with a chamber or socket 2, the wall of which is stayed and reinforced by a metallic ferrule 3. The said socket 2 receives the supporting stem or shank 4 of the bluing holder or receptacle, which stem or shank is formed by the intertwined inner ends of diverging wire spring arms 5 and 6 and is fastened in practice in said socket in any preferred manner. The arms 6 above the intertwined ends is curved outwardly as shown at 5', which serves to give said arms a springing action when the implement is opened or closed. The arms 5 and 6, respectively, carry the sections 7 and 8 of a bluing holder or receptacle, each of which preferably consists of an annular body formed of sheet metal and closed at its outer side by a strainer diaphragm 9 of cloth, wire or any other suitable material which will per-

mit free inlet of the water to the receptacle and free diffusion of the coloring material and retain all particles of abnormal size which are liable to spot the clothes.

The sections 7 and 8 of the receptacle are suitably fixed to the spring arms 5 and 6 and are adapted to be normally forced apart or held open thereby, the inner end of one receptacle being made somewhat smaller than the inner end of the other receptacle and is provided with a surrounding stop flange 17 so that the two will closely fit together, when the spring arms are compressed to bring them in engaging relation the flange 17 serving to prevent inward movement of the section 8 into the section 7. A sliding ring or compressor 10 engages the arms and is adapted when moved outwardly and inwardly thereon to force the receptacle sections closed and permit them to open in an obvious manner. The ferrule 3 reinforces the socket to prevent any liability of breakage of the wall thereof from strain under pressure from the stem 4 when the device is in use or accidentally struck against an interfering object.

Secured to the upper ends of the arms 5 and 6 are reinforces 16 which in turn are secured to the peripheries of the holders 7 and 8. The reinforces add strength to the holders and also prevent the detachment of the arms therefrom by constant use of the device.

The handle 1 is longitudinally cored to receive a magazine tube 11 having a closed inner end 12 and an outwardly projecting threaded end 13 adapted to receive a closing screw cap 14 carrying an eye or suspension device 15 of any suitable character to adapt the device to be suspended from a suitable support when not in use. Bluing material in the form of disks or cubes or in any other preferred form may be stored in the magazine 11 for use as occasion requires. It will thus be seen that a supply of the bluing material may be stored in the bluing device in such manner as to be protected from deterioration or injury, and the size of the magazine will permit of the storage of enough of the bluing material therein to supply a family of ordinary size for a long period.

It will be apparent that the device may be manufactured and sold at a comparatively low cost, and its manifold advantages will be readily appreciated.

Having thus described the invention, what is claimed as new, is:—

A bluing device comprising a handle with a socket in its upper end, a pair of arms spirally intertwined at their lower ends to provide a shank which is screwed into said socket, the arms above the shank being curved outwardly which serves to give the same springing action, bluing holders provided with strainers on their outer sides, reinforces on one portion of the peripheries

to permit of securing the upper ends of the arms to the holders, one of the holders having a surrounding peripheral stop flange, and a compressor slidably mounted on the 15 arms, substantially as specified.

In testimony whereof I affix my signature in presence of two witnesses.

MINARD F. WOOD.
